[57] **CLAIM**

The ornamental design for a shower stall, as shown and described.

DESCRIPTION

FIG. 1 is a perspective view taken from the top, front and right side of a shower stall embodying my new design, the corresponding perspective view taken from the top, front and left side being the mirror image of FIG. 1;

FIG. 2 is a top plan view thereof;

FIG. 3 is a front elevational view thereof;

FIG. 4 is a left side elevational view thereof, the right side being the mirror image of the left side;

FIG. 5 is a cross-sectional view taken on line 5—5 of FIG. 3;

FIG. 6 is a rear elevational view thereof;

FIG. 7 is a bottom plan view thereof; and,

FIG. 8 is an enlarged fragmentary view of the seating and shelf region taken in perspective from the top, left side and front thereof.
